DESIGN FOR A SPORT ENSEMBLE

David S. Roseman, New York, N. Y.

Application December 30, 1936, Serial No. 66,804

Term of patent 3½ years

To all whom it may concern:

Be it known that I, David S. Roseman, a citizen of the United States of America, residing in Manhattan, in the county of New York and State of New York, have invented a new, original, and ornamental Design for a Sport Ensemble, of which the following is a specification, reference being had to the accompanying drawing, forming part thereof, wherein,

I claim:

The ornamental design for a sport ensemble, substantially as shown.

DAVID S. ROSEMAN.
